FIG. 3.

UNITED STATES PATENT OFFICE.

HENRY FERMIER, OF MAHANOY CITY, PENNSYLVANIA.

SLIDING DOOR.

1,371,553.

Specification of Letters Patent. Patented Mar. 15, 1921.

Application filed August 7, 1920. Serial No. 401,952.

To all whom it may concern:

Be it known that I, HENRY FERMIER, a citizen of the United States of America, residing at Mahoney City, in the county of 5 Schuylkill and State of Pennsylvania, have invented certain new and useful Improvements in Sliding Doors, of which the following is a specification.

This invention relates to sliding doors and 10 has special reference to a sliding door of the general type used on freight cars, in barns and in other like situations.

One important object of the invention is to improve the general construction of devices of this character.

A second important object of the invention is to provide an improved latch arrangement for sliding doors of this character whereby a door having both bodily sliding 20 movement and lateral swinging movement at the bottom may be so controlled that the same latch member controls both movements in such manner that the sliding movement may be restrained or may take place either 25 with or without swinging movement as desired.

A third important object of the invention is to provide an improved door of this character wherein rollers or wheels will act both 30 above and below the supporting rail so that overturning of a freight car, as in a wreck, will not cause the door to either jam or jump its rail or track.

With the above and other objects in view, 35 as will be hereinafter apparent, the invention consists in general of certain novel details of construction and combinations of parts hereinafter fully described, illustrated in the accompanying drawings and specifically claimed.

In the accompanying drawings like characters of reference indicate like parts in the several views, and:

Figure 1 is a side elevation of the improved door as applied to a freight car, the hood covering the upper part of the door being omitted.

Fig. 2 is a section on the line II—II of Fig. 1, the hood being shown.

50 Fig. 3 is a detail side elevation of the lower part of the door open and showing the latch in various positions as indicated by full and dotted lines.

Fig. 4 is a section on the line IV—IV of 55 Fig. 3.

Fig. 5 is a section on the line V—V of Fig. 4.

Fig. 6 is a detail perspective view of the bottom or guide rail used herewith.

In the embodiment of the invention herein disclosed there is shown a freight car 10 having a door opening 11. It is to be understood that this is merely typical of any structure having a door opening such as a barn, a mill wall either inside or out or in 60 fact any structure whatever.

Surrounding the door opening on the side next to the door are metallic wear plates 12 above the top one of which is firmly secured a beam 13 having fixed to its upper 70 surface a rail 14 preferably formed from round bar metal. At 15 is a door of ordinary construction and of proper size to cover the door opening. To the upper part of this door are firmly secured hangers 16 carrying rollers 17 which rest on the rail 14 and are grooved to cause them to fit properly in position. The upper part of the door is also provided with reinforcing or bracing plates 18, one on the front and one on the 75 back, and between these plates are carried rollers 19 which do not bear normally against the beam 13, the vertical spacing of the rollers 17 and 19 being such as to permit only a slight swinging movement of the 80 bottom of the door while effectively preventing displacement of the rollers 17 or the rollers 19 from their proper position relative to the beam and rail. The whole of the parts connected with or related to the 85 upper part of the door are protected from the weather by a suitable hood 20.

On the lower edge of the door are also secured reinforcing plates, the inner plate 21 projecting below the bottom part of the 90 door while the outer plate 22 comes flush with such bottom edge. Below the door a Z-bar 23 is firmly secured to the car with its upper edge flush with or just a little 95 below the bottom of the door. By means of this arrangement the bottom of the door may be swung out and back to a limited extent as when ice or snow has clogged this guide rail. To further assist in clearing the bottom guide an opening 24 is made in the 100 web of the Z-bar so that ice or snow or other material accumulating in the guide may be swept through this opening. Adjacent the outer flange the Z-bar is provided with a series of spaced slots 25 for selective en- 105 110

gagement by a latch bar 26 movable vertically through a guide 27 fixed on the door. The upper end of this latch bar has pivotal connection with a latch lever 28 pivoted at 5 one end by a suitable pivot 29 to the door. This latch lever moves behind a guide or cover plate 30 and behind this cover plate are located spaced spring plungers 31 which are selectively engaged in a recess 32 formed 10 in the latch lever so that the lever may be held in desired position. In the present instance I provide two of these plungers, one to hold the lever in the position shown at A in Fig. 3 and the other to hold it in 15 the position shown at B in such figure. In the position shown at A the door is locked from all movement by engagement of the latch bar in one of the openings 25; in that shown at B the latch bar is drawn up sufficiently to release from the opening and 20 permit the door to slide but still will project downward behind the flange of the Z-bar guide thus preventing swinging of the bottom. In the position C the latch bar is 25 raised sufficiently to clear the top of the Z-bar flange and thus permits swinging movement of the door as well as sliding movement thereof. In order to hold the door locked a keeper 33 is provided on the 30 door jamb so that when the lever 28 is engaged in the keeper it may be held down by an ordinary car seal 34 passed through a suitable opening 35 in the keeper.

There has thus been provided a simple and 35 efficient device of the kind described and for the purpose specified.

It is obvious that many minor changes 40 may be made in the form and construction of the invention without departing from the material principles thereof. It is not therefore desired to confine the invention to the exact form herein shown and described but it is wished to include all such as come within the scope claimed.

45 I claim:

1. In combination, a door support, a door 40 dependent from and slidable along said support, said door being arranged for swinging movement of its lower edge transverse the path of its sliding movement, and a single

55 latch means arranged to selectively permit and restrain sliding movement of the door and to selectively permit full swinging movement, prevent all swinging movement and permit limited swinging movement of said door.

2. In combination, a door frame, a door 60 supporting member extending along the door frame near its upper end, a sliding door suspended from said member and having its bottom edge free to swing to and from the frame, a guide rail below the bottom edge of the door and provided with latch receiving openings, said guide rail having an upstanding flange at its outer 65 edge, and a latch bar mounted on the door and engageable selectively in said openings, said latch bar having a vertical amplitude of movement to permit such engagement, to lie behind the flange and permit sliding 70 movement of the door while preventing swinging movement thereof and to be raised above the flange and permit both sliding and swinging movement of the door.

3. In combination, a door frame, a door 75 supporting member extending along the door frame near its upper end, a sliding door suspended from said member and having its bottom edge free to swing to and from the frame, a guide rail below the bottom edge of the door and provided with latch receiving openings, said guide rail having an upstanding flange at its outer edge, a latch bar mounted on the door and engageable selectively in said openings, said latch bar having a vertical amplitude of movement to permit such engagement, to lie behind the flange and permit sliding movement of the door while preventing swinging movement thereof and to be raised 80 above the flange and permit both sliding and swinging movement of the door, a latch lever pivoted to the door and having the latch bar pivoted between its ends, a guide 85 for the free end of the latch lever, and means to selectively and releasably hold the latch lever in a plurality of desired positions.

90 In testimony whereof I affix my signature.

HENRY FERMIER.
